CLAIM

The ornamental design for a flexible enclosure for a recreational structure, shown and described.

DESCRIPTION

FIG. 1 is a perspective view of a flexible enclosure for a recreational structure according to the subject matter disclosed herein;

FIG. 2 is a top view of a flexible enclosure for a recreational structure according to the subject matter disclosed herein; and,

FIG. 3 is a side view of a flexible enclosure for a recreational structure according to the subject matter disclosed herein.

The ornamental design, which is claimed, is shown in solid lines in the drawings.

The broken line showing is included for the purpose of illustrating and forms no part of the claimed design.
